UNITED STATES PATENT OFFICE

2,092,053

METHOD AND MEANS FOR SHAPING THE
BOTTOMS OF SHOESHerman A. Davenport, Brockton, Mass., assignor
to United Shoe Machinery Corporation, Paterson, N. J., a corporation of New Jersey

Application August 19, 1935, Serial No. 36,769

18 Claims. (Cl. 12—34)

This invention relates to the manufacture of shoes and has more particular reference to the application of shaping or leveling pressure to the bottoms of shoes. The invention, in certain important aspects, is especially applicable to the manufacture of shoes the outsoles of which are secured by stitches passing through both the outsoles and the insoles, such as Littleway shoes, while in other aspects it is not thus limited but is generally applicable to the manufacture of shoes of various kinds.

The operation of shaping or leveling the bottoms of shoes has heretofore commonly been performed either by the use of direct pressure, i. e., pressure applied simultaneously to the different portions to be pressed, or by the use of pressure applied progressively to the different portions. In direct pressure leveling, heavy pressure must necessarily be used in order that when distributed over the different portions to be pressed the pressure per unit of area will be sufficient to effect the desired results. A metal mold or form of the desired shape is utilized to apply the pressure, and the shoe is usually not mounted upon the wooden last upon which it was made but is supported by a metallic foot or last since there would be danger of breaking the wooden last by the application of such heavy pressure. In order to avoid the expense of providing a large number of metal forms and lasts for shoes of various sizes and styles, and for other reasons, it is accordingly a frequent practice to level shoes by progressive pressure. In applying pressure progressively to different portions of the sole, the shoe, mounted upon its last is operated on by means (generally a roll) which, while it accommodates itself in some measure to the bottom of the last, is not the equivalent of a form complementary to the shape of the last bottom. For some kinds and conditions of work it has therefore proved to be difficult to produce as even and smooth a bottom surface as desired in a leveling operation when the leveling has been thus performed between parts one only of which, i. e., the last, was a reproduction of the shape desired. In the manufacture, for example, of women's shoes of the lighter grades in which the outsoles are secured by through-and-through stitching, such as Littleway shoes, the stitching, which unites the outsoles to the uppers and insoles, frequently causes ridges to be formed in the outsoles. It has been found that these ridges, as well as other inequalities or bunches which may be formed in the outsole by reason of the irregularity or unevenness of the

shoe materials between the insole and the outsole, are sometimes not entirely removed in the leveling operation and as a result the bottom of the shoe is not in the best possible condition for succeeding bottom-finishing operations. 5

The present invention provides a novel method of pressing the bottoms of shoes whereby as the desired contour is imparted to the bottom face of the sole all of the inequalities, bunches or ridges that may exist therein are entirely removed. In accordance with this method, in one important aspect, there is applied to the bottom of the shoe a form having a contour substantially complementary to the desired contour of a shoe bottom and through this form leveling pressure is applied progressively, as by a roll, to different portions of the shank and forepart of the sole to level them. For best results the form should be of sufficiently hard and tough material to prevent any substantial deformation or indentation thereof by irregularities in the sole as the leveling pressure is applied through the form to the sole, and yet it should be flexible and resilient enough to permit it to be used for leveling shoes of different sizes and shapes. It has been found that balata meets these requirements, this material being preferably not subjected to vulcanization but molded into the desired shape under pressure and a moderate degree of heat after the resins have been largely removed therefrom. For the practice of this method there may advantageously be utilized machines of the type used heretofore to apply rolling pressure automatically for leveling the outsole, the form being interposed between the roll and the shoe bottom for transmitting the pressure of the roll to the sole. 25 30 35

In a further important aspect, the invention provides novel means for carrying out the above-mentioned method, including a form of substantially hard non-brittle elastic material of the required contour through which the pressure of a leveling roll is transmitted progressively to different portions of the sole to press it free from inequalities and to impart, for example, to its forepart and shank portions, the desired shape. Preferably the form has an upper face which normally is substantially straight widthwise of the form and is also substantially straight lengthwise of the form forwardly and rearwardly of the junction of its forepart and shank pressing portions to cause the roll to apply substantially uniform pressure along the forepart and shank portions of the sole and also to permit tipping of the roll to impart the desired transverse curva- 40 45 50 55

ture to the shank portion without danger of interference between the roll and the side of the shoe. Such a form may be conveniently attached to a flexible saddle such as used heretofore between a leveling roll and the sole of a shoe, the saddle being utilized to apply a substantial amount of direct pressure through the form to the sole to hold the shoe against movement relatively to the last as the pressure is applied progressively by the roll to different portions of the sole. Thus any danger of distorting the shoe or of straining the sole, especially in the case of shoes that are made of light materials, such as women's shoes, is avoided.

15 The invention will now be more particularly described by reference to the accompanying drawing and pointed out in the claims.

In the drawing,

Fig. 1 is a view in side elevation of a portion 20 of a leveling machine of the roll type adapted for use to accomplish the objects of this invention;

Fig. 2 is a perspective view of a form adapted to be interposed between the leveling roll and the bottom of a shoe, the form being shown as attached to a saddle as in Fig. 1;

Fig. 3 is a cross-sectional view illustrating the shaping of the shank portion of the sole; and

Fig. 4 is a longitudinal sectional view illustrating the shaping of the forepart of the sole.

30 The machine shown is of the same general type as that shown and described in detail in various Letters Patent of the United States including Letters Patent No. 1,667,761, granted on May 1, 1928 upon an application of E. E. Winkley and 35 H. A. Davenport. In machines of the type above referred to, the shoe is supported on a jack comprising a heel post 10 and a toe support 12 and the jack is oscillated about a pivot 14 to carry the shoe lengthwise back and forth under a 40 spring-pressed roll 16, carried by an arm 18, the arm being so controlled as to tip the roll about an axis extending lengthwise of the shoe in time relation to the movements of the jack and thus to position it for operating in the desired manner 45 on different portions of the sole. For moving the arm 18 downwardly to carry the roll into operative position in automatically determined time relation to the movements of the jack and for controlling the pressure of the roll on the shoe in 50 the course of the leveling operation, there is provided mechanism which is substantially like that shown in the above-mentioned Letters Patent but modified in accordance with the disclosure of Letters Patent No. 1,685,387, granted on September 25, 1928 upon an application of E. E. Winkley and F. V. Hart. The arm 18 is carried by a vertically movable arm 19 having pivotally connected to it a vertical link 20 to the lower end of which there is pivotally connected on arm 22 55 pivoted at 24 on the frame 26 of the machine. A heavy spring 28 rests at its lower end on the arm 22 and supports at its upper end a plunger 30 which is arranged to be forced downwardly by a lever 32 pivoted at 34 on the frame 26 and connected by a link 36 to an arm 38 pivoted at 40 on the frame. The arm 38 carries a cam roll 42 arranged to engage a cam 44 which is mounted on a shaft 46 and is rotated once in each cycle of operations of the machine. The shape of the 60 cam 44 is such that at a predetermined time in each oscillatory movement of the jack the pressure of the roll on the shoe bottom is diminished or relieved, the release of leveling pressure usually occurring as the roll approaches the ball line of 65 the shoe in the inward movement of the jack and

again as the roll approaches the ball line of the shoe in the outward movement of the jack. Formed integral with or secured to the cam 44 is a second cam 48 arranged to be engaged by a cam-roll 50 carried by one arm of a bell-crank 5 lever 52, pivoted at 54 on the frame 26. The bell-crank lever 52 has a second arm 56 and connected to the arm 22 is a gravity latch 58 which may be swung downwardly to engage the arm 56 or upwardly into a position permitting free relative pivotal movement between the arm 22 and the lever 52. The shape of the cam 48 is such that with the latch 58 in the position shown in Fig. 1 after the roll 16 has been moved downwardly into operative position, its pressure on the 10 shoe will be maintained substantially constant during the whole leveling operation. For further information with reference to the details of the construction thus far described, reference may be made to the Letters Patent hereinbefore 15 mentioned.

In leveling the bottoms of shoes, it is particularly desirable that all the inequalities or bunches that may exist in the sole by reason of the irregularity or unevenness of the shoe materials between the insole and the outsole be effectively smoothed down and that the ridges that are caused by the stitches which unite the sole to the upper, for example, in shoes that are stitched through and through, be pressed and smoothed 20 out so as to impart to the shoe an even and regular bottom surface. In accordance with this invention, the required pressing or leveling of the sole so as to remove all inequalities, bunches or ridges therein is effected by the use of a form 25 which, as herein illustrated, is adapted to cover the shank and forepart of the shoe bottom and to be interposed between the roll and the bottom of the shoe for transmitting the pressure of the roll to the sole. To this end there is provided a 30 form 60 having a contour substantially complementary to the desired contour of a shoe bottom and made of sufficiently hard material to prevent any substantial deformation thereof by irregularities in the sole under the pressure of the roll. 35 The invention is not limited to the use of a form of any particular material but balata has been found satisfactory for the purpose in view. Preferably this material, which is a gum obtained from a sapotaceous tree, is not subjected to vulcanization but is molded into the desired shape under pressure and a moderate degree of heat after the resins have been largely removed therefrom. A 40 form made of this material is sufficiently tough to prevent impressions being formed therein by irregularities in the sole and yet is sufficiently non-brittle, elastic, and resilient so that it may readily be used for leveling the bottoms of shoes of various 45 sizes and styles. As herein shown, the form is substantially plano-concave in cross-section laterally of the shoe, its upper surface being substantially straight widthwise of the form and also substantially straight lengthwise of the form 50 forwardly and rearwardly of the junction of its forepart and shank portions, the upper surfaces 55 of the forepart and shank portions of the form being inclined somewhat relatively to each other in the general direction of the length of the form. In order to avoid any possibility of staining the sole such as might occur by direct contact of the 60 balata with the tempered sole, the sole-pressing face of the form is covered with a layer of canvas 62 to which there is cemented a thin layer of leather, preferably pigskin 64. The canvas is 65 firmly united to the balata in the operation of 70

molding the balata and serves as a backing to which the pigskin can be satisfactorily cemented. The cover of pigskin is provided with marginal flaps 66 which extend upwardly and are laid inwardly over the upper face of the form which has secured to it and to the marginal flaps 60 a layer of canvas 68. The pigskin layer, which is very thin, is compressed and becomes very hard in the leveling operation. For applying the form to the bottom of the shoe there is cemented to the upper layer of canvas 68 a saddle 70 frequently used heretofore in machines of the type herein shown to assist in holding the shoe on the jack. The saddle 70 is made of flexible leather and is connected at the opposite sides of the shank and forepart of the shoe by springs 72 (Fig. 1) to a hand lever 74 which is utilized to apply the saddle and form tightly over the shoe bottom, as shown in Letters Patent No. 1,704,822, granted on March 12, 1929 upon an application of mine. With the saddle and form in place on the sole, the leveling roll 16 is made to act in the usual manner over the shank and forepart, the machine preferably being adjusted, by movement of the latch 58 into the position shown in Fig. 1, so that the pressure of the roll is maintained substantially constant on the form as oscillatory movements about the axis 14 are imparted to the jack to carry the shoe rearwardly and forwardly under the roll. The form bridges any of the minor irregularities of the shoe bottom so that as the pressure of the roll is applied progressively through the form to different portions of the forepart and shank of the sole, these irregularities are pressed and smoothed out thereby resulting in imparting the desired evenness to the tempered sole. By reference to Fig. 4 it will be observed that because of the shape of the form there will be no abrupt dropping off of the roll into the shank such as might result in damage to the last or loss of tension of the spring 28 and consequently loss of pressure of the roll on the shank portion of the sole because of the lowered position of the roll. Furthermore, in operating upon narrow shank shoes the necessary tipping movements laterally of the shoe are imparted to the roll to apply the pressure to the opposite marginal portions of the sole without danger of interference between the roll and the side of the shoe. It will be understood that as the saddle is pulled in a direction heightwise of the shoe through the springs 72 by the downward swinging movement of the lever 74, the form is pressed firmly against the shoe bottom and exerts direct pressure on the forepart and shank portions of the sole. In the operation of the machine as leveling pressure is applied progressively by the roll 16 through the form 60 to different portions of the forepart and shank of the sole, the form acts to prevent movement of the shoe relatively to the last and to hold the treated portions pressed firmly against the last while other portions are being acted upon by the roll. Thus any danger of distorting the shoe on the last or of straining the sole especially in the case of shoes that are made of light materials, such as women's shoes, is avoided.

While the form is disclosed as made of balata, any material having the required characteristics can be used. While the invention is herein illustrated in its application to the manufacture of shoes the outsoles of which are secured by stitches passing through both the outsoles and the insoles such as Littleway shoes, it is not necessarily limited to the manufacture of shoes of that particular type since it is contemplated that the inven-

tion may likewise be used with advantage in the manufacture of other kinds of shoes including welt shoes and also turn shoes.

Having described the invention, what I claim as new and desire to secure by Letters Patent of the United States is:

1. That improvement in methods of pressing the bottoms of shoes which consists in applying leveling pressure progressively to different portions of the forepart, including the toe end, and the shank of a shoe sole by the use of a roll and a form interposed between the roll and the bottom of the shoe throughout the length of the forepart and in the shank for transmitting the pressure of the roll to the sole, the form having a contour substantially complementary to the desired contour of a shoe bottom and being of sufficiently hard material to prevent any substantial deformation thereof by irregularities in the sole under the pressure of the roll so as to remove said irregularities.

2. That improvement in methods of pressing the bottoms of shoes which consists in applying to the entire forepart and shank portions of the bottom of a shoe a form of hard non-brittle elastic material having a contour substantially complementary to the desired contour of the entire forepart and shank portions of a shoe bottom, and operating through the form while the form remains in contact with all portions of the forepart and shank of the sole to apply pressure progressively to different portions of the forepart and shank of the sole to level them.

3. That improvement in methods of pressing the bottoms of shoes which consists in applying over the entire forepart and shank portions of a shoe sole a form of material harder than the shoe sole, said form being molded approximately to the desired contour of the entire forepart and shank portions of a shoe bottom, and applying to said form rolling pressure to cause the form to press and smooth out any irregularities that may exist in the forepart and shank portions of the sole.

4. That improvement in methods of pressing the bottoms of shoes which consists in applying to the bottom of a shoe substantially from its toe to its heel end a form of unvulcanized balata having a contour substantially complementary to the desired contour of a shoe bottom from its toe to its heel end, and applying pressure to different portions of the form successively to level the entire forepart and shank portions of the shoe sole.

5. That improvement in methods of pressing the bottoms of shoes which consists in applying pressure heightwise of a shoe to the entire forepart and shank portions of the shoe sole by the use of a form of hard non-brittle flexible resilient material molded approximately to the desired contour of the entire forepart and shank portions of a shoe bottom, and while thus pressing the sole applying additional pressure progressively to different portions of the form successively to assist in removing any irregularities that may exist in the forepart and shank portions of the sole.

6. That improvement in methods of pressing the bottoms of shoes which consists in applying to the bottom of a shoe a form of unvulcanized deresinated balata molded approximately to the desired contour of the forepart and shank portions of a shoe bottom, and applying rolling pressure to the form to level the forepart and shank portions of the shoe sole.

7. That improvement in methods of pressing the bottoms of shoes which consists in applying to the bottom of a shoe a molded form of material harder than the sole, the form extending 5 along the shank and forepart of the shoe substantially from the heel breast line forwardly to the toe end of the shoe and having a sole-pressing face substantially complementary to the desired contour of the forepart and shank portions of a shoe 10 bottom, pulling upon said form in the direction of the height of the shoe to hold it tightly against the bottom of the shoe, and while thus pulling upon the form applying thereto rolling pressure to level the forepart and shank portions of the 15 sole.

8. That improvement in methods of pressing the bottoms of shoes which consists in applying over the bottom of a shoe a saddle to which there 20 is secured a molded form of unvulcanized balata from which the resin has been largely removed, the form having a sole-pressing face substantially complementary to the desired contour of the forepart and shank portions of a shoe bottom, pulling 25 upon the saddle at the opposite sides of the shank and the forepart in the direction of the height of the shoe to hold the form tightly against the bottom of the shoe, and while thus holding the form pressed against the bottom of the shoe applying rolling pressure thereto to level the shoe 30 bottom.

9. In a machine for pressing the bottoms of shoes, the combination with a shoe support and a roll for applying leveling pressure progressively to the forepart and shank portions of the shoe 35 sole, of a form mounted on the machine so as to be interposed between the roll and the shoe bottom along the whole of the forepart and shank portions of the shoe bottom for transmitting the pressure of the roll to the sole, said form being 40 molded approximately to the desired contour of the whole of the forepart and shank portions of a shoe bottom and being of sufficiently hard material to prevent any substantial deformation thereof by irregularities in the sole under the 45 pressure of the roll so as to remove said irregularities.

10. In a machine for pressing the bottoms of shoes, a shoe support, a form of material harder than the sole of a shoe for engaging the whole of 50 the forepart and shank portions of the sole, said form having a contour substantially complementary to the desired contour of the whole of the forepart and shank portions of a shoe bottom, means for applying the form to the bottom of a 55 shoe on said support, and means for applying rolling pressure to the form to level the forepart and shank portions of the sole.

11. In a machine for pressing the bottoms of shoes, the combination with a shoe support and 60 means for applying leveling pressure progressively to the forepart and shank portions of the sole of a shoe on said support, of a form of hard non-brittle elastic material mounted on the machine so as to be interposed between the pressure- 65 applying means and the bottom of the shoe for transmitting the pressure of the pressure-applying means to the whole of the forepart and shank portions of the sole, said form having a contour substantially complementary to the desired 70 contour of the forepart and shank portions of a shoe bottom.

12. A machine for pressing the bottoms of shoes having, in combination, a shoe support and a roll

relatively movable to level the forepart and shank of the sole of a shoe on said support, and a form of hard non-brittle elastic material for transmitting the pressure of said roll to all portions of the forepart and shank of the sole, said form having a sole-pressing face substantially complementary to the desired contour of all portions of the forepart and shank of a shoe bottom and an upper face substantially straight rearwardly of its forepart portion. 5

13. A machine for pressing the bottoms of shoes having, in combination, a shoe support and a roll relatively movable to level the forepart and shank of the sole of a shoe on said support, and a form for transmitting the pressure of said roll 10 to all portions of the forepart and shank of the sole, said form having a sole-pressing face substantially complementary to the desired contour of a shoe bottom and an upper surface formed by two flat faces extending lengthwise of the form 15 at an angle to each other. 20

14. A machine for pressing the bottoms of shoes having, in combination, a shoe support and a roll relatively movable to level the sole of a shoe on said support, and a form of unvulcanized 25 balata molded approximately to the desired contour of the forepart and shank portion of a shoe bottom for transmitting the pressure of said roll to all portions of the forepart and shank of the sole. 30

15. A machine for pressing the bottoms of shoes having, in combination, a shoe support and a roll relatively movable to level the forepart and shank of the sole of a shoe on said support, a form of hard non-brittle flexible resilient material arranged to extend along the shank and forepart of the shoe bottom for transmitting the pressure of the roll to the sole, said form having a sole-pressing face shaped approximately to conform 35 to the desired contour of a shoe bottom and 40 covered with a thin layer of leather, a sheet of flexible material arranged to be interposed between said form and the roll, and means for applying to the sheet of flexible material at each side of the shoe a pull in the direction of the 45 height of the shoe.

16. For use in a machine for pressing the bottoms of shoes, a saddle of flexible leather having secured thereto a form of hard non-brittle resilient material adapted to cover the bottom of the 50 shank and forepart of a shoe, said form being shaped approximately to the desired contour of a shoe bottom and having its sole-pressing face covered with pigskin. 55

17. For use in a machine for pressing the bottoms of shoes, a saddle of flexible leather having secured thereto a form of material harder than the leather of the sole of the shoe operated upon and adapted to cover the bottom of the shank and forepart of a shoe, said form being 60 shaped approximately to the desired contour of a shoe bottom. 65

18. For use in a machine for pressing the bottoms of shoes, a form of hard non-brittle elastic material having a sole-pressing face shaped approximately to conform to the desired contour of the forepart and shank portions of a shoe bottom and a face opposite its sole-pressing face formed by substantially plane surfaces inclined 70 relatively to each other in the general direction of the length of the form. 75
